PERSPECTIVE DRAWING MACHINE

Daniel J. McQuaid, Sr., and Frederick William Riehl, Denver, Colo.; said Riehl assignor to said Daniel J. McQuaid

Application December 27, 1949, Serial No. 135,194

2 Claims. (Cl. 33—77)

1

This invention relates to various forms of drawing machines and tools especially adapted to facilitate the making of perspective drawings.

Previously many different types of drawing machines have been devised and quite a few of the prior types of drawing machines have been designed to facilitate the making of perspective drawings. Predominantly, however, the prior machines have been concerned with making perspective drawings from orthographic projections by means of linkage arrangements whereas only a few have been adaptable to the making of perspective drawings directly. Since the mechanism necessary to facilitate the making of perspective drawings from orthographic projections is relatively complex, machines of this general type have not received commercial adoption proportionate to the potential market for perspective drawing machines. It is believed that this failure to gain widespread usage has been the result of several important factors. In order to fully realize the sales advantages to be gained from wide scale usage, it is believed that a perspective drawing machine should be accurate, easy to operate, fast, portable, readily understandable, durable, economically constructed, easily adaptable to any commercial type drawing board, adaptable for making various types of perspective drawings, and useful in the drafting room as an aid to the performance of routine drafting duties as a replacement for various conventional drafting tools. It is believed that all previous designs of perspective drawing machines have failed to capture the potential market for such machines by reason of failures to satisfy one or more of the foregoing requirements.

Realizing that a machine which satisfied all of the above requirements would be highly desirable, the present inventors have put forth concerted effort and research in developing the perspective drawing machines now presented. These machines are designed to satisfy the following objectives:

To provide a perspective drawing machine that is light in weight and economical of construction having relatively few parts.

To provide a perspective drawing machine having straight edge guide members disposed thereon to facilitate the drawing of lines radiating from a common axis which may be used as a 50 vanishing point.

To provide a perspective drawing machine which incorporates mechanisms for moving such axis to desired positions on or off of the drawing surface of the machine thereby placing the van-

2

ishing points for the perspective drawing in desired positions.

To provide a type of perspective drawing instrument which may be readily attached to conventional types of drawing boards.

To provide a perspective drawing machine incorporating means for automatically removing the guide edges used in drawing out of contact with the drawing board when not in use, together with further means in specific forms of the invention for accurately repositioning the guide members in their exact previous position when the drawing operations are to be continued.

To provide a perspective drawing machine 15 having at least one pivoted guide member, a straight edge of which is aligned with the pivot or axis of said guide member to facilitate the drawing of lines radiating from said pivot or axis.

To provide extension members for perspective drawing machines capable of supporting a guide member of the foregoing type in various selected positions around, above, over or on the drawing board.

Further objects and advantages of the present invention will be apparent from the appended description and drawings in which:

Fig. 1 is a dimetric drawing of a first embodiment of this invention;

Fig. 2 is a dimetric representation of a further embodiment of this invention;

Fig. 3 is a dimetric drawing showing modifications and improvements for the basic form shown in Fig. 1;

Fig. 4 is an exploded view showing the component parts of the pivot head utilized in the embodiment shown in Fig. 3;

Fig. 5 is a dimetric representation showing further modifications and attachments for the drawing machine of Fig. 3;

Fig. 6 is a dimetric drawing showing various modifications and improvements of the basic form shown in Fig. 2;

Fig. 7 is an exploded view of the component parts for the pivot head shown in Fig. 6;

Fig. 8 is an enlarged view showing additional features of the form shown in Fig. 6;

Fig. 9 is a dimetric representation of modifications of the form shown in Fig. 6 showing one novel use of the present type of machine;

Fig. 10 is a dimetric drawing of a further modification of the basic form shown in Fig. 2;

Fig. 11 is a cross sectional elevation taken along the line 11—11 of Fig. 10 showing structural features of this embodiment;

Fig. 12 is an exploded view of the pivot head construction for the embodiments shown in Fig. 10;

Fig. 13 is an exploded view showing the structure of the slide guide and position return device shown in Fig. 10;

Fig. 14 is an elevational view of a drawing machine made in accordance with this invention showing the drawing surface thereof in raised position and further showing the utility of this invention in aiding the drawing of perspective views in which one vanishing point is approximately five times further away from the central axis of the figure being drawn than the other vanishing point;

Fig. 16 is a dimetric representation of a basic form of this invention in which a single drawing edge may be selectively supported by pivots establishing the desired vanishing points;

Fig. 16 is a dimetric drawing showing a modification of the basic invention wherein the drawing edge is supported between spaced plates having scale markings thereon;

Fig. 17 is a plan view showing one use of the basic equipment of this invention in which triangles are shown as being secured to the drawing edges to facilitate the drawing of systems of vertical or other lines and in which a separate locking device is provided for securing the drawing edges in adjusted position;

Fig. 18 is a plan view showing a further use of the basic devices of this invention in which the support head is moved up and down the edge of the drawing surface to facilitate the drawing of a system of parallel lines;

Fig. 19 is a plan view showing the use of the basic mechanisms of this invention to establish scalable perspective drawings through use of the third movable vanishing point;

Fig. 20 is a plan view showing the use of the basic drawing machine of this invention together with triangles of special angularity to establish desired systems of parallel lines;

Fig. 21 is a plan view showing the use of equipment provided in accordance with the principles of this invention to make one point perspective drawings;

Fig. 22 is a plan view showing the use of the basic mechanisms of this invention to make three point perspective drawings;

Fig. 23 is a dimetric representation showing the attachments necessary to convert the usual drawing board so as to make such drawing board useful in accordance with the principles of this invention; and

Fig. 24 is a plan view showing the various types of objects which may be drawn to the full size of the drawing surface with the aid of the perspective drawing machine of this invention.

Briefly stated the present invention provides in its simplest form a guide edge which is mounted for rotation about a bearing or pivot member in such manner that the guide edge is aligned with the axis of said pivot so that lines drawn with the aid of the edge will all radiate from the axis. Further provision is made for the selective placement of extension arms outwardly from the edges of the drawing board as supports for the pivot member and attached guide edge. In all embodiments the pivot member is slidably engaged with the extension arms to permit lateral adjustments in the placement of the pivot axis.

As refinements and improvements of the basic principle of this invention the inventor provides various attachments for positioning the pivot

axis and therefore the vanishing points of a perspective drawing above, on, or at positions removed from the drawing board. Further improvements provide for the automatic removal of the guide members from the face of the drawing board whenever desired, while cooperative mechanisms are provided to accurately reposition the guide members in their previous positions. Through use of such novel arrangements and attachments the present inventors are able to facilitate the making of various regular types of drawings as well as distinctive perspective drawings.

Referring now to Fig. 1 it will be noted that the inventors provide edge members 11 made of metal or other wear resistant materials for attachment to a conventional type drawing board 12. The edge members 11 are provided with a plurality of openings 13 in the outwardly disposed faces thereof. These openings 13 are threaded or otherwise adapted to engage and support extension rods 14. At least one end of the extension rods 14 is adapted for cooperative reception in the openings 13 so that the rods will be securely held in positions extending laterally at 90° from the edge 11. In this first embodiment at least two rods 14 are placed in adjacent openings 13 so that the rods will extend in relatively close parallel relation. A bearing block 16 or pivot support member having holes 17 therethrough is provided for sliding engagement with said rods 14. Preferably the holes 17 are of but slightly larger diameter than the diameter of the rods 14 so that the friction resistance between the rods 14 and 17 will be adequate to resist unintentional reciprocal movement of the block 16. A guide member 18 having a straight edge 19 is mounted on the bearing block 16 for pivotal movement about a pivot member 20 having an axis through the bearing block 16 at right angles to the flat upper face thereof. The axis of the pivot is in line with the straight edge 19 so that all lines drawn with the aid of the edge 19 will in effect radiate from the said pivot axis. Though the details of structure are not shown in Fig. 1, a locking device or nut 21 is provided for securing the guide member 18 in its adjusted position with respect to the pivot axis.

The detailed features of a locking device suitable for this particular application are shown in Fig. 4 where it will be noted that a hole 22 is drilled through the block 16 at right angles to the face of the block. A pivot pin 23 which is of a diameter which will fit snugly through the hole 22 is provided for engagement in the hole 22. In addition to the hole 22 the pivot pin 23 passes through flat washers 24 and lock washer 26 which are separately arranged and adapted to provide for free rotational movement of the guide edge support member 27 about the pivot 23 even though the nut 28 is snugly engaged with the pivot bolt 23 to complete a relatively rigid assembly. It should be understood, however, that with this particular arrangement it is possible to engage the nut 28 securely on the pivot bolt 23 so that the guide support 27 will be held in rigid position. For normal drawing operations, however, the tension on the nut 28 is adjusted so that the lock washer 26 will tend to offer only slight frictional resistance to the movement of the guide support 27. A modification of the form shown in Fig. 1 which fully utilizes the pivot and bearing block assembly described is shown in Fig. 3. In this figure the drawing board 12 is shown with a stand

29 providing adjustable, tilting support for the drawing board 12 through use of radius members 31 and lock nuts 32. Actually the support described is of conventional design; however, the drawing board 12 usually mounted on such support 29 has been modified through the provision of wear resistant edge members 11 equivalent to those shown in Fig. 1. Further, the openings 13 are provided in the edges 11 for the identical purpose of providing support for the parallel extension rods 14. As before, the extension rods 14 slidably support the pivot support bearing blocks 16 about which guide members 18 are freely rotatable. In this figure the utility of providing a plurality of extension rod supports 13 is apparent inasmuch as it is here shown that the guide edges 18 may be supported for rotation about pivot axes at various positions around a drawing board 12. With the particular arrangement shown wherein the guide edges 18 are mounted for pivotal movement about pivot axes positioned beyond the lateral sides of the drawing board 12, it will be apparent that two point perspective drawings may be readily executed by adjusting the positioning of the guide edges 18 associated with the said pivots. In addition where the pivot axis is positioned along the top edge of the drawing board, it will be readily apparent that the making of one point perspective drawings will be greatly aided. If desired, all of the guide edges 18 shown may be used at one time to execute three point perspective drawings.

An additional attachment for the drawing machine described is shown in Fig. 5. In this figure it should be noted that additional extension rods 14 are provided to support blocks 33 to which a cross member 34 is secured. The cross member is provided with a longitudinally extending slot 36 through which a pivot 37 may be extended. A guide edge 18a is preferably secured to the pivot 37 so that the forward edge 19a is in alignment with the axis of the pivot 37. A locking knob 38 is threadedly engaged to the pivot 37 so that the guide edge 18a may be readily placed in desired positions and secured in such positions by tightening the lock nut 38 into engagement with the cross member 34.

A modification for the basic arrangement originally disclosed in Fig. 1 is shown in Fig. 2. In this figure it will be noted that the drawing board 12 is provided with wear resistant edge members 11 having holes 13 therein. As changes in the original structure, however, this particular embodiment utilizes only a single extension rod 14 as a support for each of the drawing guide edges. In order to fully utilize the advantages to be gained from the use of single support extension rods 14, the structure of the pivot support member is modified so that the bearing block 39 is provided with only a single through hole 41. As before, the diameter of the hole 41 is just slightly greater than the diameter of the extension rods 14 so that the block 39 will fit snugly on the extension rod 14 for reciprocal motion therealong. A support plate 42 which is secured to the bearing block 39 by screws 43 (not shown in this figure) or other similar means and a pivot pin 44 extends downwardly through a protractor 46, the support plate 42 and into a bearing block 39. As in the previous instance, the forward edge 19b of the guide member 18b is aligned with the axis of the pivot 44. One advantage inherent in this structural form is shown in Fig. 2 where it will be noted that the bearing block 39, support plate 42 and guide member 18 may be rotated around the 70

extension rod 14 to move the guide member 18 to an alternative position out of contact with the drawing board 12.

Refinements of the basic form shown in Fig. 2 are presented in Fig. 6 wherein it will be noted that the inventors provide a drafting table 47 as support for drawing board 48. Essentially the form shown in this figure is adapted for making perspective drawings on a relatively larger scale than the form shown in Fig. 2. Accordingly more rigid extension pieces 49 are provided to extend laterally from the table 47. To further assure rigidity of structure, extension support legs 51 having a base plate 52 are adjustably engaged with the extension pieces 49 by means of block clamps 53. Since the support legs 51 pass freely through the block clamps 53, the clamps may be adjusted to any desired height above the supporting floor by merely loosening and tightening thumb screws 54. A cross rod 56 is provided which passes through bearing members 57 which are movable along the extension pieces 49 to adjusted positions as desired. Preferably the cross rod 56 is freely rotatable in the bearing blocks 57 to facilitate the removal of the guide members 18c from the face of the drawing board 48.

The further structural elements necessary to provide for the automatic removal of the guide members 18c is shown in the exploded view of the pivot head as shown in Fig. 7. Here it will be noted that the inventors provide a pivot head support block 58 having an opening 59 transversely therethrough in which the cross rod 56 is engaged and secured by tightening of the set screw 61. An upwardly disposed edge of the support block 58 is drilled and tapped to provide threaded holes 62 for the reception of support plate securing screws 43 and a central hole 63 for engaging and holding the pivot pin 44. A support plate 42 passes downwardly over the pivot pin 44 when it is in its engaged position in the opening 63, and flat head screws 43 adapted for engagement in the holes 62 secure the support plate 42 in position above the support block 58. A balance rod 64 extends from the support plate and a counter-balancing weight 66 having an opening 67 transversely therethrough is adapted to slide along the length of the balance rod 64 to be secured in desired positions by tightening the set screw 68. A protractor member 69 having scale markings 71 on its upper face to indicate radial positions of the guide member 18c is secured to the support plate by a plurality of additional flat head screws 43. A central hole 72 through the protractor plate 69 permits the placement of the protractor 69 over the pivot pin 44. A spacer 73 having a central opening 74 is likewise placed over the pivot pin 44 to substantially cover the heads of the screws 43 while still exposing to view the scale markings 71 on the protractor plate 69. The guide member 18c having an opening 76 disposed centrally in a disk shaped portion 77 of the guide member 18c is likewise placed over the pivot pin 44 for rotation thereabout. An additional spacer 73 having an opening 74 therein is likewise positioned over the pivot pin 44 as is a lock washer 78, a flat washer 79, adjusting nut 81 and a lock nut 82. In its final assembled relation the guide member is freely rotatable about the pivot pin 44 unless it becomes desirable to tighten the adjusting nut 81 to hold the guide member 18c in fixed position. With this particular arrangement of parts, it will be readily observed that the counterbalance

weight 66 may be positioned along the balance rod 64 so as to raise the guide members 18c out of contact with the drawing table 48 whenever the draftsman using the guide members releases his hold thereon. In the alternate position substantially as shown, the guide members 18c present no obstruction to the view or further work on the drawing being executed.

In Fig. 8 this same arrangement of parts is shown in larger detail than in Fig. 6. Also in this figure it is shown that the inventors may, when they deem it necessary, attach a coil spring 83 to the cross rod 56 to dampen the normally fast movement of the guide members 18c to their alternate out of use position and to prevent the continued swinging of the guide members 18c after they have raised to the out of use position.

In Fig. 9 the inventors show further modifications of the basic form shown in Fig. 2. In this particular drawing the mechanism is shown as associated with conventional types of shadow box equipment. Accordingly the stand 29 is shown as supporting a central shadow box 84 of relatively large dimension. This box is of conventional structure and design inasmuch as a sheet of plate glass 86 is supported above a light source (not shown) which is properly connected to a source of electric power by means of wires 87. As shown, a sheet of drawing paper 88 may be supported above the glass plate 86. Smaller shadow boxes 89 are placed along the lateral edges of the central box 84. These side boxes 89 are likewise provided with transparent plates 91 and suitable light source (not shown) therebeneath. These light sources are also connected with a source of electric power by means of wires 87. The guide members 18c which are adapted to facilitate the drawing of lines converging at vanishing points on either side of the paper 88 are supported in their adjusted positions on extension rods 14 which are secured in holes 13 provided in the sides of the shadow boxes 89. As in Fig. 6, support legs 51 are provided to give greater strength and rigidity to the extension rods 14. The structure for the guide member supports is substantially the same as that shown in Figs. 6, 7 and 8 except that a segment protractor 92 of larger dimension than the protractor 69 is provided. However a modified type of support for a center guide member 18c is shown. In this form a strap member 93 is provided which has a plurality of holes 94 therein. The strap member is secured to a hinged block 96 which is likewise secured to one of the extension rods 14 extending upwardly from the top edge of the shadow box 84. It is intended that a segment protractor 97 may be selectively positioned and secured to the strap member 93 at any of the successive holes 94 inasmuch as the pivot pin 98 for this form of mount is removable. At the same time that the protractor is moved the guide member 18c will likewise be moved to rotate about the pivot pin 98 in its newly adjusted position. Since the block 96 is hinged and since a balance rod 99 and balance weight 101 are provided it will be apparent that whenever the guide member 18c is released by the draftsman the guide member, the protractor and the strap 93 will all be elevated to an out of use position. Accordingly it is likewise possible with this design to completely clear obstructions from the drawing surface of the paper 88.

A novel use of this drawing machine together with the shadow box equipment shown is indi-

cated on Fig. 9. This use accomplishes the reproduction of perspective drawings or photographs in enlarged scale. The operation is carried out in the following manner:

Two drawings of reduced scale or photographs 102 are placed above the transparent plates 91 of the opposite shadow boxes 89. The pivot support heads of the drawing machine are then adjustably positioned so that the axis of the pivot corresponds to the apparent vanishing point for the photograph. The guide members are then brought down into position so that the forward drawing edge 18c of the guide members is aligned with principal lines in the photograph. A line 15 is then drawn on the face of the sheet of paper 88 using the edge of the guide member to determine the direction and position of the line. The opposite pivot head support member is then adjusted so that the axis of the pivot will correspond to a second apparent vanishing point for the photograph mounted above the opposite shadow box 89. The guide member 18c is then placed in position so that the edge 18c passes along the point of termination in the photograph 102 of the line previously extended by the first guide member. This placement will determine the extent or length of the line being drawn on the paper 88. In similar manner further lines 20 in the photograph are extended and positioned until all of the detailed features of the photographs are duplicated in enlarged scale on the face of the paper 88, the product being a perspective view line drawing.

Figs. 10, 11, 12 and 13 show other modifications and improvements of the basic disclosure in Fig. 2. Here extension rods 14 engaged in holes 13 in edge pieces 11 on the board 12 provide support for pivot head structures substantially as shown in Fig. 7, the detailed parts of which are shown in Fig. 12. As shown in Fig. 12, the applicants here provide a bearing block 103 having a transverse opening 104 therethrough of diameter slightly greater than the diameter of the extension rod 14 so that the bearing block 103 will be freely movable along the extension rod. A further hole 106 is provided through the upper face of the bearing block 103 for the reception of the end of a pivot bolt 107. A spacer 108, a support blade 109, a segment protractor 111, washers 112 and a guide head support 113 are all likewise provided with holes through which the pivot bolt 107 will extend. When in assembled relation the guide head 113 is rotatable about the pivot bolt 107 while the protractor and support plate remain stationary.

A guide edge 114 is provided having openings 116 therein for cooperative positioning with the openings 117 and the guide head support 113. Screws or other means are used to secure the 60 guide edge 114 to the guide edge 113 when these holes are in aligned position. Since the principal feature of the present modification is the provision of a second guide arm which is rotatable about the pivot which is slidable longitudinally of the guide edge 114, rails 118 are provided which are adapted to be secured on the guide edge 114 by means of screws 119 or the like. Preferably the rails 118 are of different size so that the rails 118a resting adjacent to the 65 guide edge 114 are of lesser width than the rails 118b mounted above the rails 118a. This size relation provides a channel 121 between the rails in which a slide member 122 may be engaged for reciprocal motion along the length of the guide 70 edge 114.

As shown in Fig. 11, the slide 122 reciprocates between the rails 118a whereas a spacer member 123 moves reciprocally between the rails 118b. It will be apparent that with this arrangement the slide 122 cannot be removed from its position between the rails 118. Slide 122 is provided with a central opening 124 adapted for the reception of one end of a pivot bolt 126. Further the slide 122, spacer 123 and a disk support plate 127 are all provided with openings through which screws 128 or other fastening devices may be passed to hold the said members in permanent arrangement. In their assembled relation a further plate 128 is positioned above the support plate 127 and a protractor 129 is positioned above the plate 128. Plate 128 is provided with an opening 131 through which the pivot pin 126 passes, and a second opening 132 adapted for the reception of the end 133 of a stop pin 134. The protractor 129 is likewise provided with a central opening 136 and an opening 137 into which the stop pin may extend. A guide arm 138 is provided having an opening 139 through which the pivot pin 126 extends, and a second opening 141 adapted to receive and hold the stop pin 134.

When in the assembled relation as shown in Fig. 10, the pivot bolt 126 may be loosened so that the guide arm 138, protractor 129, and plate 128 will rotate freely. With the pin in its engaged position the angularity of the guide arm 138 is adjusted until it assumes a desired position. The pivot bolt is then tightened to secure the plate 128 in its adjusted position. Thereafter the stop pin 134 may be lifted so that the end 133 comes out of contact with the hole 132 in plate 128. Since the pin 134 is out of engagement with the hole 132 the guide arm 138 may be freely rotated to other positions. If desired the guide arm may be put into a position along the guide edge 114 and the mechanism may be used in the manners previously described. Whenever it is desired to re-execute additional lines that were drawn with the guide arm in its adjusted position, the guide arm may be rotated to that position at which time the pin 134 will again move into engagement with the hole 132 and plate 128 to secure the guide arm 138 accurately in its original position. Since the guide arm 138 will be used principally for making vertical lines or other sets of parallel lines, it is essential that means be provided for securing the guide arm 114 in accurate predetermined positions. This is possible in several different ways with the structure shown. First, bushings 142 as shown in Fig. 12 may be secured on the extension rod 14 by tightening set screws 143 mounted on the bushings 142. Locking these bushings 142 in place will prevent translational movement of the block 103 along the extension rod 14 while pivotal movement about the rod 14 is still possible. While the angular position of the guide member 114 can be fixed by tightening the nut 144 on the pivot bolt 107, the excessive tightening necessary is usually not desirable. Accordingly the inventors provide a clamp 146 having upper and lower spring members 147 which may be slipped over the edge 11 of the body 12 and over the face of the guide member 114 to securely hold the guide member in a fixed position.

While this one particular arrangement is shown it should be obvious that other means such as C clamps or the like could be provided and further that a pin locking device similar to

pin 134 could be positioned to hold the guide head support 113 in fixed position with respect to the protractor and plate 111 and 109 respectively. Whatever the means used for securing the guide member 114 in position may be, it is obvious that reciprocal motion of the slide 122 between the guides 118 will move the guide edge 138 through a plurality of parallel positions.

It will be obvious that the various forms of the present invention are adaptable for many different utilitarian purposes. Likewise it will be noted that while the various mechanisms are specifically designed for aiding the production of perspective drawings, these same tools are adaptable for the accomplishment of various routine drafting operations.

Among the special jobs which will be facilitated by this drawing machine are the making of perspective drawings in which the position of either one, two or three vanishing points may be adjusted to positions above, on or removed from the drawing surface. Further when the drawing surface is arranged in raised position the mechanisms of this invention will facilitate the making of accurate layouts and guide lines for paintings, etchings, murals or various types of commercial art design. Another very important use for this machine is in making accurate lithographer's line drawings for color separation work and other printing mats. Likewise this machine can be used to make exploded drawings of machine parts from smaller drawings or photographs as well as for retouching work in photographs.

A special feature of this machine is embodied in its inherent usefulness to make perspective drawings that are scalable and accurate inasmuch as the scales actually diminish in the direction of the vanishing point. These scalable drawings can be made the entire size of the drawing board since it is possible to accurately place the vanishing points at selected positions away from the drawing surface. While the machine may be used directly to facilitate the making of perspective drawings, it is also well adapted to the making of conventional types of perspective charts as necessary to satisfy the requirements of unusual positions of view. When made, charts of this type are useful in conventional manner as guide lines to be placed under drawing paper when sketching perspective drawings.

It will be apparent that these devices are also adaptable to various other modifications and changes which will further increase the utilitarian purpose of this invention. All such modifications and changes as are within the scope of the hereunto appended claims are deemed to be a part of this invention.

What is claimed is:

1. A perspective drawing machine comprising a body having a drawing surface, a shadow box having a transparent surface and a source of illumination therebeneath, means for securing said shadow box to said body adjacent the drawing surface, an extension member supported by the shadow box disposed outwardly therefrom, a block adjustably supported by said extension member, a pivot member mounted on said block, guide means mounted for rotating movement about said pivot having an edge thereof in alignment with the axis of said pivot for facilitating the drawing of lines on said drawing surface that radiate from said axis and are in alignment with

11

the principal lines of objectives placed and viewed above said shadow box.

2. A perspective drawing machine, comprising a rectangular frame, including a flat top surface centrally of the frame for the support of material to be drawn on, and an adjoining surface for the support of copy to be drawn, a plurality of openings at intervals along the length of the frame exteriorly of said drawing and copy-supporting surfaces, two bodies adapted for attachment to opposite sides of said frame and a third body adapted for attachment to the top edge of said frame, each including at least one rod for selective penetration of said openings, and guide means in pivotal connection with each said body having a straight edge in radial alignment with the pivotal axis and extending over the drawing surface, and said side-mounted guide means also extending over the copy surface so as to permit perspective enlargement of 20 the copy lines on said drawing surface.
